UNITED STATES PATENT OFFICE.

ALFRED W. GARITY, OF PITTSFIELD, MASSACHUSETTS.

AUTOMOBILE-SIGNAL.

1,232,023.

Specification of Letters Patent.

Patented July 3, 1917.

Application filed February 29, 1916. Serial No. 81,229.

To all whom it may concern:

Be it known that I, ALFRED W. GARITY, a citizen of the United States, residing at Pittsfield, in the county of Berkshire and State of Massachusetts, have invented certain new and useful Improvements in Automobile-Signals, of which the following is a specification.

This invention relates to an improved signal which is intended to be used in connection with an automobile to indicate the direction in which the machine is going to turn and the principal object of the invention is to provide an improved type of illuminated box and to also provide improved means for mounting the same and improved means for lighting the electric bulbs when the signal is turned to the desired position.

Another object of the invention is to so mount the signal or indicator proper as to yieldably hold the same in a set position and to return the indicator to the normal position after being moved to indicate the direction in which the machine is about to turn.

Another object of the invention is to provide improved contacts so that when the indicator is turned to an adjusted position the bulbs will be illuminated.

Another object of the invention is to provide improved operating means for turning the indicator, the operating means being yieldably held in the normal position and returned to the normal position after being moved to an adjusted position.

Another object of the invention is to so construct this operating means as to permit of its being connected with the steering post of the automobile where it will be convenient to reach.

This invention is illustrated in the accompanying drawings, wherein:—

Figure 1 is a view showing an automobile in side elevation and provided with the improved indicating means,

Fig. 2 is a longitudinal sectional view through one of the signals,

Fig. 3 is a fragmentary view showing the contact means for the bulbs in section,

Fig. 4 is a perspective view of the indicator which is shown mounted in the housing in Fig. 2, the contact means which also serves as a pivot pin for the indicator being removed,

Fig. 5 is a sectional view taken along the line 5—5 of Fig. 2,

Fig. 6 is a sectional view taken along the line 6—6 of Fig. 2,

Fig. 7 is an enlarged sectional view of one of the insulating plugs used in connection with this invention,

Fig. 8 is an enlarged view in elevation of one of the contact pins used in connection with this invention,

Fig. 9 is a perspective view of one of the insulator blocks used in connection with this invention and shown in Fig. 6.

The signals which are designated in general by the numerals 15 and 16 in Fig. 1 may be placed in any convenient position upon the body portion of the automobile, they having been shown upon the forward and rear mud guards in the drawings. Conduits 17 and 18 lead from these forward and rear signals and terminate adjacent the lower end of the conduit 19 leading from the actuating mechanism indicated in general by the numeral 20 in Fig. 1. This actuating mechanism is connected with the steering post 21 close to the steering wheel 22 and it will thus be seen that when the driver of the car is about to turn a corner he can very readily reach the handle 23 of the actuating mechanism to turn the same. From an inspection of Fig. 1 it will be readily seen that this mechanism is so constructed that it may be readily connected with any car now in use and that therefore no special construction of body portion is necessary in order to permit the device to be used.

The signals 15 and 16 are constructed alike and therefore a detail description of one will suffice for both. The housing indicated in general by the numeral 24 is open at one side as shown in Figs. 5 and 6 and is provided with base flanges 25 extending from the end wall or head 26 so that the housing may be connected with the mud guard or other part of the automobile. This housing will therefore serve to throw the light in the desired direction and thus permit a person to easily see the light shown on the indicator contained in the housing.

The indicator denoted in general by the numeral 27 is rotatably mounted in the housing 24 and includes a rectangular body portion formed principally of sheet metal but having two of its walls indicated by the

2
 numerals 28 and 29 formed of glass and having "Left" and "Right" painted upon them as shown in Fig. 4. The heads 30 which are perforated as shown at 31 are provided with flanges 32 and 33 which engage the glasses 28 and 29 and hold the glasses in engagement with the heads to form the walls of the body portion. Spring catches or clips 34 are carried by the flanges 32 and engage the edge of glass 28 so that when the indicator is turned to exhibit the glass 28 there will be no danger of this glass slipping out of place.

In order to rotatably mount the indicator there has been provided stems 35 and 36 which extend through the openings 31 in the heads 30 and are provided with collars 37 which are secured to the inner faces of the heads 30 by means of rivets or other fasteners 38. Spring 39 is wound upon the pin 35 and has one end connected with the inner end portion of the pin and the other end connected with the head of the housing 24 thus yieldably holding the indicator in a position to prevent the glass walls from showing through the open side of the housing. The pin 36 is hollow as shown in Fig. 3 and is provided with a dividing block 40 which carries the contacts 41 engaged by the inner end of the contact shoe or pin 42 which passes through the insulating collar 43. This contact pin 41 engages the contact of the bulb 44 when the bulb is screwed into the socket formed in the inner end of the pivot pin 36 and therefore when the indicator is turned to the proper position the bulb will be illuminated. The nipple 45 which forms part of stem 36 is separated from the block 40 by means of the padding 46 as shown. This nipple 45 and the reduced end 47 of the pin 35 are rotatably mounted in the openings 48 of the heads 26, the reduced ends of the pins 35 and 36 being provided so that the indicator cannot have longitudinal movement in the housing.

From an inspection of Figs. 2 and 6 it will be seen that the head 26 through which the end of pin 36 passes carries an insulating block 49 having bearings 50 provided with threaded openings 51 through which the contact pins 52 extend. These contact pins are provided with enlarged heads 53 so that they may be connected with the wire 54 leading from the battery 55. The second wire 56 of the battery is connected with the contact point 57 which engages the bulbs as shown in Fig. 3 and therefore when the arm 58 is in engagement with one of the pins 52 a circuit will be completed through the lamp to illuminate the same. Under normal circumstances spring 39 will hold the indicator in a position to prevent engagement of contact arm 58 with either of the contact pins 52 and therefore the lamp will not be continually burning thus using up current.

From an inspection of Fig. 1 it will be seen that the wires 54 and 56 leading from the battery or other source of power 55 are passed through the conduits 17 and 18 which also serve as a conduit for the line 59. 70 This line 59 has its end portion with the lug 60 formed upon pivot pin 36 and therefore when the line is drawn the two indicators will be simultaneously moved to a position to indicate that the pin is to turn 75 to the right or to the left. In order to draw the line 59 there is provided a drawing line 61 which passes through the conduit 19 and is connected with the actuating mechanism.

When in use this signal is mounted as shown in Fig. 1 so that a person in front of the car can see the signal 15 and a person behind the car can see the signal 16. 85 When the driver is going to turn to the left the handle 23 will be moved thus drawing line 59 to rotate the two indicators 27 to the position to show the plate carrying the word "Left." At the same time the contact arm 58 will engage one of the contact points 52 90 and the lamp will be illuminated. If the driver is to turn to the right he will move the handle still farther thus giving the indicators a greater amount of rotation and moving them to the position shown in Fig. 4. 95 The plate carrying the word "Right" will then appear and the contact arm will engage the second contact point 52 thus illuminating the lamp. After the turn has been made the handle will be released and springs 68 100 and 39 will return the handle and the two indicators to the normal position, in which position the lamp will not be illuminated thereby preventing waste of current.

What is claimed is:—

1. A direction indicator comprising a housing, an indicator mounted within the housing to be capable of turning movement, contacts carried by said housing and spaced apart therein, a lamp carried by the indicator, a contact mounted in conjunction with the indicator and connected with the lamp, means arranged in conjunction with said indicator for normally resiliently holding the same in a relation that the contact thereof occupies a neutral position with respect to the contact carried by the housing, and means by which the indicator is manually movable against the tension of said last mentioned means to bring the indicator to predetermined settings and to also move the contact of the indicator into engagement with the contacts of the housing.

2. A direction indicator including a signal having a housing, indicating means positioned within said housing and including a body portion with transparent walls, pivot pins extending from said body portion and rotatably mounted in openings formed in said housing, a contact carried by said hous- 125 130

ing, a contact carried by one of the pivot pins, a bulb carried by said last mentioned pin and engaged with the contact thereof, an electric circuit including wires connected with said contacts, means for yieldably holding said indicating means in a neutral position where the contact of the pin thereof is spaced from the contact of the housing, and means for rotating said indicator to move the same to an adjusted position and bring the contact of the same into engagement with the contact of said housing.

3. A direction indicator mechanism including a signal having a housing open at one side, an indicator positioned in said housing and comprising a body portion, pivot pins for said body portion rotatably carried by said housing, one of said pivot pins having a socket formed in its inner end portion, an insulator block positioned in said pin, a contact extending from said socket through said pin, a contact pin carried by said block, a contact arm extending from said last mentioned pin, a spring wound upon the other of said pivot pins and having one end portion connected with the pin and the other end portion with said housing, said spring serving to yieldably hold said indicator in a neutral position, and means for rotating said indicator in said housing.

4. A direction indicator mechanism including an indicator having pivot pins carried at the ends thereof, means by which said indicator is mounted through the me-

dium of said pivot pins to be capable of turning movement, a contact carried by said indicator, a contact mounted at a fixed point, an electric bulb carried by said indicator connected with the contact thereof, an electric circuit having wires connecting said contacts, means for yieldably holding said indicator in a neutral position in which the contact thereof is spaced from the fixed contact, and means for moving said indicator to an adjusted position against the action of said last mentioned means and to bring the contacts into engagement.

5. A direction indicator mechanism including a signal having a housing open at one side, an indicator positioned in said housing and comprising a body portion, pivot pins for said body portion rotatably carried by said housing, one of said pivot pins having a socket formed in its inner end portion, an insulator block positioned in said pin, a contact extending from said socket through said pin, a contact pin carried by said block, a contact arm extending from said last mentioned pin, and means for rotating said indicator in said housing to bring the contact to a position to be energized.

In testimony whereof I affix my signature in presence of two witnesses.

ALFRED W. GARITY.
